UNITED STATES PATENT OFFICE.

WILLIAM FRANCIS JAMES AND WILLIAM THOMAS DEACON, OF VELASCO, TEXAS.

ROWING APPLIANCE.

No. 895,863.

Specification of Letters Patent.

Patented Aug. 11, 1908.

Application filed December 20, 1907. Serial No. 407,389.

To all whom it may concern:

Be it known that we, WILLIAM FRANCIS JAMES and WILLIAM THOMAS DEACON, citizens of the United States, and residents of 5 Velasco, in the county of Brazoria and State of Texas, have invented a new and Improved Rowing Appliance, of which the following is a full, clear, and exact description.

This invention is an improvement in rowing appliances for row-boats, and is of the 10 character which embodies oars each made in two sections pivoted together, and so supported that when the oars are pulled, the handles and blades thereof move in the same 15 direction, whereby the operator faces the bow in propelling the boat and is thus enabled to observe the direction of travel.

The invention resides in certain special 20 features of construction and combination of parts as will be hereinafter particularly described and claimed.

Reference is to be had to the accompanying 25 drawings forming a part of this specification, in which similar characters of reference indicate corresponding parts in all the views.

Figure 1 is a plan of a row-boat having our 30 improved propelling means applied thereto, showing the sections of one of the oars in alinement and in full lines at one side of the boat, and the sections of the other oar at the 35 opposite side of the boat in dotted outline and in a position when the oar is at the end of the stroke; Fig. 2 is a fragmentary longitudinal section through one of the oars, on the line 2—2 of Fig. 1; and Fig. 3 is a similar sectional view on the line 3—3 of Fig. 1, looking in the direction of the arrow.

For convenience of description only one 40 oar and the means for applying it to the boat, will be described, it being understood that the opposite oar is of the same construction.

In the gunwale of the boat is revolvably 45 mounted an oar-lock 5, and at each side thereof are attached the free ends of outwardly-converging connecting-arms, forming a bracket 6, the connection between the bracket and the boat being preferably effected by providing wood screws, bolts or other 50 like devices 7, which pass through the apertured extremities of the bracket arms; the bolts projecting upwardly from the gunwale and having the heads thereof arranged slightly above the top faces of the arms, as 55 shown in Fig. 3. The apertures in the arms

through which the bolts pass are of greater diameter than the body of the bolt, whereby the bracket has a limited rocking movement, permitting the outer portion thereof to be depressed, as indicated in dotted outline in Fig. 3. Where the arms of the bracket join 60 together, an oar-lock 8 is revolvably mounted, and is preferably held against separation from the bracket by a cross-pin or other equivalent device 9.

Through the oar-locks 5 and 8 pass the oar, 65 made in two sections, an outer section 10 and an inner section 11, the said sections being pivotally connected together between the oar-locks to swing in a lateral direction. This 70 connection between the two sections of the oar is made by riveting or otherwise securing the opposed ends of the oar sections in metal sockets 12 which have overlapping projecting portions 13, through which a pivot-bolt 14 passes. The sockets 12 are of such 75 length that when connected together by the pivot-pin or bolt they will pass through the oar-locks and thus receive the wear. The inner socket 12 is connected with the oar-lock 5 by a pin or bolt 15, the same being arranged at substantially right-angles to the shank of the oar-lock, thus adapting the oar 80 to be swung in a vertical plane. This construction of the oar and its application to the 85 boat causes the blades of the oars, when pulled, to travel in the same direction as the handles, which makes it possible for the oarsman to face the bow while rowing in the usual manner, and is thereby enabled to observe 90 the direction of the boat's travel. The limited pivotal or rocking movement of the brackets permits of the oars being dipped into and out of the water the same as in the ordinary rowing movement.

The apertures of the brackets 6, through 95 which the bolts 7 pass, will preferably be of such size as to freely pass over the heads of these bolts, whereby the entire mechanism, with the exception of the bolts 7, may be 100 bodily lifted from the boat if desired to remove the oars. This construction obviously enables the oars to be applied and removed with despatch.

The appliance as shown and described 105 while being the preferred manner of carrying out our invention, may nevertheless be modified in particulars within the scope of the appended claims.

Having thus described our invention, we 110

claim as new and desire to secure by Letters Patent:

1. In a rowing appliance for row-boats, a bracket consisting of outwardly-converging arms connected together and having means connecting the free ends thereof to the boat, permitting of a limited swinging movement of the bracket vertically, an oar-lock supported in the connecting portions of said arms, an oar-lock revolvably supported by the boat between said arms, and an oar passing through the oar-locks, composed of two sections pivoted together between said locks, adapting the sections of the oar to swing laterally.
2. In a rowing appliance for row-boats, devices projecting upwardly from the gunwale of the boat and having heads, a bracket having apertures adapted to pass over said heads and have a limited rocking movement thereunder, an oar-lock revolvably mounted on the outer portion of the bracket, an oar-lock revolvably supported on the boat, and an oar passing through said oar-locks, composed of two sections pivoted together between said locks.
3. In a rowing appliance for row-boats, a

bracket connected with the side of the boat and adapted to swing vertically, an oar-lock carried by the bracket, an oar-lock carried by the boat, sockets passing through said locks, having overlapping portions pivoted together, and an inner and an outer portion of an oar respectively secured within said sockets.

4. In a rowing appliance for row-boats, upwardly-projecting bolts secured to the boat having heads, a bracket having a limited rocking movement on the bodies of said bolts under said heads, and an oar composed of two sections pivoted together to swing laterally, one of said sections having a revolute connection with the bracket and the other of said sections having a revolute connection with the boat.

In testimony whereof we have signed our names to this specification in the presence of two subscribing witnesses.

WILLIAM FRANCIS JAMES.
WILLIAM THOMAS DEACON.
